Inventor

Fred Miller,

UNITED STATES PATENT OFFICE.

FRED MILLER, OF CORNING, OHIO.

FLIGHT FOR ENDLESS CONVEYERS.

SPECIFICATION forming part of Letters Patent No. 501,289, dated July 11, 1893.

Application filed February 4, 1893. Serial No. 460,968. (No model.)

To all whom it may concern:

Be it known that I, FRED MILLER, a citizen of the United States, residing at Corning, in the county of Perry and State of Ohio, have invented certain new and useful Improvements 5 in Flights or Buckets for Endless Conveyers; and I do hereby declare the following to be a full, clear, and exact description of the invention, such as will enable others skilled in the 10 art to which it appertains to make and use the same.

The object of my invention is to economically construct a flight or bucket that may be used advantageously with an endless band 15 composed of the ordinary chain links.

In the accompanying drawings, forming a part of this specification, Figure 1 is a perspective view of one part or wing of the flight. Fig. 2 is a front elevation of the flight complete. Fig. 3 is an edge view looking down 20 at the top of Fig. 2; and Fig. 4 is a sectional view taken on the line $x-x$ of Fig. 2 or 3.

In Figs. 3 and 4 I have shown the flight applied to fragments of the chain.

As illustrated in the drawings, the flight or bucket is composed of two similarly constructed separable parts or wings 11 adapted to be secured together so as to extend on opposite sides of the chain. Each wing or part 25 1 consists of a plate of metal of substantially rectangular form having its outer edge slightly curved as shown at 2 so as the better to gather and retain the material as it is drawn along a channel or trough and on its inner edge a tongue 3 struck up out of the metal, standing at right angles to the plane of the plate. When the tongue 3 is struck up out 30 of the plate, tongues 4 remain above and below the tongue 3. The tongues 3 and 4 4 are perforated as shown at 5 and 6 for the passage of fastening bolts.

To form the complete flight or bucket two 45 of the plates 1 are put together so that the tongues 4 lap and the tongues 3 stand parallel to each other on the same side of the flight,

but the position of the bolt holes 6 in tongues 4 is such that when the bucket is put together there is a space between tongues 3 for the reception of link 7 of an endless chain. The lapping tongues 4 are secured together 50 by means of bolts 8 and nuts 20, substantially as shown, while the tongues 3 are secured in position against the sides of link 7 by bolt 19 and nut 21. The rear link 10 serves as a stop for the bucket on link 7. 55 Every bucket on the chain may be put together at regular intervals in the same way.

What I claim as my invention, and desire to secure by Letters Patent, is—

1. In an elevator bucket or flight, the plate 60 1 having at one edge tongues 4, a recess intermediate said tongues adapted to receive a chain link, and a transverse tongue 3 at the edge of the recess, substantially as described.

2. In an elevator bucket or flight, the plate 65 1 having at one edge tongues 4, a recess intermediate said tongues adapted to receive a chain link, a transverse tongue 3 at the edge of the recess, and the outer curved edge 2, substantially as described. 70

3. A bucket or flight for elevators comprising two plates 11 each having at their inner edge two overlapping tongues 4, a recess intermediate said tongues adapted to receive a chain link, and a tongue 3 transverse 75 to the plane of the plate at the edge of the recess, substantially as described.

4. A bucket or flight for elevators comprising two plates 11 each having at their inner edge two overlapping tongues 4, a recess intermediate said tongues adapted to receive a chain link, the transverse tongue 3 at the edge of said recess, and the outer curved edge 2, substantially as described. 80

In testimony whereof I affix my signature in 85 presence of two witnesses.

FRED MILLER.
